UNITED STATES PATENT OFFICE

EDWARD J. WEIKERT, OF OFFERLE, KANSAS

SIGN

Application filed April 2, 1928. Serial No. 266,722.

The present invention relates to improvements in signs and has reference more particularly to a signboard that is capable of being placed adjacent a roadway where the same can be readily and easily viewed.

One of the important objects of the present invention is to provide a sign which is simple in construction, inexpensive, strong and durable and further well adapted to the purposes 10 for which it is designed.

Other objects and advantages will become apparent during the course of the following description.

In the accompanying drawings, forming a 15 part of this specification, and in which like numerals indicate like parts throughout the same:

Figure 1 is a rear elevation of the sign embodying my invention,

20 Figure 2 is a side elevation thereof,

Figure 3 is a fragmentary top plan view, and

Figure 4 is a fragmentary vertical sectional view showing the manner in which the sign- 25 board is secured to the uprights.

In the drawings wherein for the purpose of illustration is shown the preferred embodiment of my invention, the numeral 1 designates generally a rectangular shaped sign- 30 board that may be constructed of wood or metal and on the front side of which is adapted to be arranged the advertising indicia. If desired, an ornamental molding may extend around the edges of the sign- 35 board. Wooden blocks such as are shown at 2 are secured on the rear side of the signboard adjacent the upper and lower edges thereof and at spaced intervals. Also secured to the rear side of the signboard are 40 the longitudinally extending angle iron bars 3, the same extending for the full length of the signboard. Securing means at the ends of the angle iron bars are shown at 4.

Additional wooden blocks 5 are secured on 45 each of the angle iron bars 3 for vertical alignment with the aforementioned wooden blocks 2, and a securing means for these blocks is shown at 6, said securing means extending through the signboard and through 50 the angle iron bars as well as the blocks in

the manner as clearly illustrated in Figure 4 of the drawings.

A plurality of elongated spaced angle iron standards or uprights 7 have their lower ends embedded in a concrete base 8 which is set in 55 the ground and these standards or uprights extend transversely of the longitudinally disposed angle iron cross bars and engage with the rear faces of the wooden blocks 2 and 5, in the manner clearly shown in the drawings, 60 and the securing means for the wooden blocks extend through the respective standards whereby said standards are spaced with respect to the signboard 1.

Diagonally arranged angle iron brace bars 65 9 which are secured at their upper ends to the upper portions of the respective angle iron standards or uprights 7 as at 10 have their lower ends disposed adjacent the rear edge portion of the concrete base 8 and the lower 70 ends of these brace bars are secured to the shorter uprights 11 that have their lower ends embedded in the rear portion of a concrete base and these shorter uprights are disposed in alignment with the respective forward and longer standards or uprights. 75

The upper end of each of the shorter uprights 11 is connected with the lower portion of the respective front upright 7 through the medium of the substantially horizontally disposed members 12 and the angularly disposed brace bars 9 are secured to the respective cross members 12 at their points of intersection as shown at 13 in Figure 2.

While I have shown the sign as having the 85 uprights or standards embedded in a concrete base, it is to be understood that they may be anchored at their lower ends in any other suitable manner. Also the sign supporting members and the braces may be constructed of wood. 90

It will thus be seen from the foregoing description, that I have provided a sign construction which will be strong and durable and while I have stated that the uprights and 95 bracing means therefore are constructed of angle iron material, the same can be formed of wood if so desired.

While I have shown the preferred embodiment of my invention, it is to be understood 100

that various changes in the size, shape and arrangement of parts may be resorted to without departing from the spirit of the invention and the scope of the appended claim.

5. What I claim is:—

In a sign, a plurality of parallel spaced angle iron standards anchored at their lower ends, a sign board, wooden blocks for disposition against the rear side of the sign board and arranged in a predetermined manner, angle iron bars extending longitudinally across the rear side of the sign board, said wooden blocks being disposed in alinement with the respective vertical standards, certain of the wooden blocks being disposed within the angle iron bars, and securing means extending through the sign board, angle iron bars, wooden blocks and angle iron standards whereby to support the sign board in spaced relation with respect to the vertical standards.

In testimony whereof I affix my signature.

EDWARD J. WEIKERT.
